UNITED STATES PATENT OFFICE.

JAMES M. WALSH, OF MILWAUKEE, WISCONSIN, ASSIGNOR TO JAMES M. WALSH CO., OF MILWAUKEE, WISCONSIN, A CORPORATION OF DELAWARE.

BREAST-STRAP SLIDE.

Application filed February 7, 1925. Serial No. 7,592.

This invention relates to improvements in breast strap slides for harness. In ordinary harness, the breast strap slide is formed of a number of parts and is not very strong at the points subjected to the greatest strain and the slides often break, and furthermore, the slides are usually provided with non-removable snap hook members having spring closed locking dogs which, when broken or weakened, require the replacement of entirely new slide members and snap hooks.

It is one of the objects of the present invention to overcome the before mentioned objectionable features and provide a breast strap slide which is so constructed as to reinforce the weak portions and to also permit the replacements of locking dog springs in a very simple manner.

20 A further object of the invention is to provide a breast strap slide in which the loop for receiving the martingale strap is positioned to equalize the strain on the breast strap slide.

25 A further object of the invention is to provide a breast strap slide having a removable snap hook so constructed that when the hook is removed from the slide, the locking dog may be easily removed from the hook to permit replacement of the spring for actuating the dog.

30 A further object of the invention is to provide a breast strap slide which is of simple construction, is strong and durable, and is well adapted for the purpose desired.

35 With the above and other objects in view, the invention consists of the improved breast strap slide and its parts and combinations as set forth in the claims, and all equivalents thereof.

40 In the accompanying drawing in which the same reference characters indicate the same parts in all of the views:

Fig. 1 is a side view of the improved breast slide and the straps connected thereto;

Fig. 2 is a central vertical sectional view thereof;

Fig. 3 is a top view of the slide member; and

50 Fig. 4 is a sectional detail view of the snap hook pivotal connection.

Referring to the drawing, the numeral 5

indicates the breast strap of a harness, 6 the martingale strap and 7 the improved breast strap slide connected thereto. Said breast 55 strap slide is formed with a medial curved slide portion 8 and opposite slots 9 of elongated form through which the breast strap 5 extends in passing beneath the slide portion 8. The slotted portions 9 extend at upward 60 and outward angles from the slide portion 8 to provide reinforcing flanges and also an easy curve for the portion of the breast strap engaged by said slide. The front and rear edge portions of the slide have downwardly 65 projecting eyed extensions 10 for receiving a bolt 11 which is threaded into the eye 10' of the rear extension. A snap hook member 12, having its upper eyed portion 13 interposed between the extensions 10, is pivotally 70 supported on the bolt 11 and depends downwardly therefrom. The throat portion 13 of said snap is closed by a dog 14 which is formed with trunnions 15 at its upper end. Said trunnions pivotally extend into recesses 75 16 formed in opposite portions of the snap just beneath the transverse eye of the snap, and in communication with said bore to permit the removal of the dog when desired. Said snap is also provided with a T-shaped 80 slot or opening 17 on one side of the eyed portion of the snap which opens into the bore forming the eye, so that when the bolt 11 is removed, the dog may be easily pushed upwardly, so that the trunnions will disengage 85 the pivot recesses 16, and the dog may then be easily separated from the snap by passing the trunnions through the upper portion of the T-shaped opening. The lower or stem part of the T-shaped opening is provided to accommodate the stem portion of 90 the dog and permit it to swing inwardly to open position. The inner portion of the dog stem is provided with an inwardly extending pin 18 for receiving a coiled spring 19 therearound which is interposed between the stem and a recessed portion 20 of the snap to yieldingly hold the dog in locking position against the end portion 12' of the snap. The dog is provided with side flanges 21 100 which extend on opposite sides of the snap to hold the harness part engaged by the snap in the lower portion of the hook part and to reinforce and guide the dog.

A martingale loop 22 formed integral with one edge of the slip portion 8 is so positioned as to reinforce the slide and equalize the strain due to its medial position. Said loop 5 forms an elongated slot 23 through which the loop of the martingale strap 6 extends as shown in Fig. 1.

As the parts are thus constructed, the slide portion is reinforced by the martingale loop, 10 and further reinforced by the bolt 11 and the downward extensions 10 which form flanges, and in case the dog spring 19 should break, it can be easily replaced by removing the bolt 11 and the dog 14.

15 The slide member can easily play on the breast strap and a wide surface is provided to prevent wear.

From the foregoing description, it will be seen that the breast strap slide is of very 20 simple construction and is well adapted for the purpose described.

What I claim as my invention is:

1. A breast strap slide, comprising a member having a curved slide portion and 25 opposite slotted portions to receive a breast strap, one edge portion of the member having a transversely extending loop for receiving a martingale strap, said transverse loop being substantially in horizontal alinement 30 with the lower curved part of the slide portion, lower parts of the slide portion having downwardly projecting eyed extensions, and a hook member pivotally connected to the eyed extensions.

35 2. A breast strap slide, comprising a member having a U-shaped slide portion open at both ends and opposite side slotted portions to receive a breast strap, one edge portion of the member medially of its height having a transversely extending loop for receiving a martingale strap, said transverse loop being substantially in horizontal alinement with the lower curved part of the slide portion, lower parts of the slide portion 40 having downwardly projecting eyed extensions, a bolt extending through the eyed extensions, and a hook member pivotally mounted on the bolt.

45 3. A breast strap slide, comprising a member having a U-shaped slide portion and opposite side slotted portions above the plane of the U-shaped part to receive a breast strap, one edge portion of the member medially of its height having a transversely extending loop for receiving a martingale strap, lower parts of the slide portion having downwardly projecting eyed extensions, a bolt extending through the eyed extensions, a hook member pivotally 50 mounted on the bolt between the eyed extensions and provided with recessed portions adjacent the bolt, and a spring actuated dog detachably and pivotally mounted in the recessed portions for yieldingly locking the throat of the hook member and

being easily detachable from said hook member when the bolt is partly withdrawn from said hook member.

4. A breast strap slide, comprising a member having a U-shaped slide portion 70 and opposite side slotted portions above the plane of the U-shaped part to receive a breast strap, one edge portion of the member medially of its height having a transversely extending loop for receiving a martingale strap, lower parts of the slide portion 75 having downwardly projecting eyed extensions, a bolt extending through the eyed extensions, a hook member pivotally mounted on the bolt between the eyed extensions and provided with recessed portions adjacent the bolt, and a spring actuated dog having trunnions which pivotally extend into the recessed portions for yieldingly locking the throat of the hook member 80 and being easily detachable from said hook member when the bolt is partly withdrawn from said hook member.

5. A breast strap slide, comprising a member having a U-shaped slide portion 90 and opposite side slotted portions above the plane of the U-shaped part to receive a breast strap, one edge portion of the member medially of its height having a transversely extending loop for receiving a martingale strap, lower parts of the slide portion 95 having downwardly projecting eyed extensions, a bolt extending through one eyed extension and having a threaded engagement with the other eyed extension, a hook member pivotally mounted on the bolt between the eyed extensions and provided with a side opening in communication with the bore through which the bolt extends, said hook member also having recessed portions opening into the bore, a locking dog having trunnions which enter the recesses through the side opening to pivotally connect the dog to the hook member, said dog 100 being detachable from the hook member when the bolt is partly removed, and a spring means interposed between the dog and the hook member for yieldingly holding the dog in a locking position.

6. A breast strap slide, comprising a member having a U-shaped slide portion 115 and opposite side slotted portions above the plane of the U-shaped part to receive a breast strap, one edge portion of the member medially of its height having a transversely extending loop for receiving a martingale strap, lower parts of the slide portion 120 having downwardly projecting eyed extensions, a bolt extending through one eyed extension and having a threaded engagement with the other eyed extension, a hook member pivotally mounted on the bolt between the eyed extensions and provided with a side opening in communication with the bore through which the bolt extends, said hook 125 member

member also having recessed portions opening into the bore, a locking dog having trunnions which enter the recesses through the side opening to pivotally connect the dog to the hook member, said dog also having an inwardly extending projection and the hook member having a spring recess, and a coiled spring surrounding the projec-

tion and extending into the last mentioned recess of the hook to yieldingly hold the dog in locking position, said dog and spring being detachable from the hook member when the bolt is partly withdrawn from the hook member. 10

In testimony whereof, I affix my signature.
JAMES M. WALSH.
